TO WESTERN ELECTRIC COMPANY, INCORPORATED, A CORPORATION OF NEW YORK.

ELECTRICAL CONTROLLING SYSTEM.

1,216,844.

Specification of Letters Patent. Patented Feb. 20, 1917.

Application filed December 8, 1914. Serial No. 876,083.

To all whom it may concern:

Be it known that I, JOHN G. ROBERTS, a citizen of the United States, residing at Dobbs Ferry, in the county of Westchester and State of New York, have invented certain new and useful Improvements in Electrical Controlling Systems, of which the following is a full, clear, concise, and exact description.

10 This invention relates to electrical controlling systems and is particularly adapted for multi-office telephone exchange systems.

In such systems it is desirable to provide connections between subscribers' lines 15 which terminate at different offices by means of two-wire interoffice trunks, and it is desirable also to use the two wires of the trunk for controlling the signals and switches involved in an established connection. It is 20 furthermore desirable to avoid the use of controlling circuits between the offices which depend upon a ground return path between the offices. In certain systems, such as semi-automatic exchanges providing operators' 25 answering equipment and automatic switches under the control of operators' senders for completing connections to wanted lines, the wanted subscribers should have control of an operator's supervisory signal, and the 30 operator should have control of the release of the automatic switches after the circuit is established. It is also desirable that the operator have control of the ringing equipment, in order to "rering" on the called 35 subscriber's line, without the necessity of first restoring the connection and building it up again. Because of the long distances between offices and high cost of trunk conductors, it is usual to form the interoffice 40 trunk conductors into a telephonic link and to unite this link inductively with the line circuits of the calling and called subscribers, current to each line being supplied by battery at the office where the line terminates.

45 It is the object of this invention to provide for the various signaling and switch controlling functions, required in an established interoffice connection in such a system, by means of a single loop controlling circuit extending over the same two wires which constitute the telephonic trunk link. In accordance, the invention provides that the trunk loop be maintained as a closed 55 controlling circuit with a source of current

included in it at one end during the entire time that the connection is set up between lines except for momentary interruptions therein by special switching apparatus at either end. This controlling circuit is entirely free from connection with ground or other common return path at the distant end. A succession of temporary changes in current produced preferably by momentary interruptions at the incoming end effect the 60 supervisory signal at the operator's end, by alternately displaying and effacing it. These current changes are preferably of different kind, such as those caused by a short interruption and one of longer duration, the 65 short ones, being say of one-tenth of a second and the longer ones say of four-tenths of a second, and means is provided whereby the called substation switch, in being closed and opened, effects the short and long 70 current changes respectively, in the trunk loop.

The control in the other direction, that is to say, from the operator's end of the trunk to the apparatus at the incoming end, is effected by similar current changes in the 75 same circuit. Thus the restarting of an automatic ringing apparatus may be effected by a short interruption in the trunk circuit at the operator's end, and the release of the 80 automatic switch or switches at the incoming end, whether the called line circuit is at the moment open or closed, may be effected by a prolonged interruption or opening of the trunk circuit at the operator's end.

This invention will be more fully understood by reference to the accompanying drawings wherein is illustrated a system of circuits and apparatus operable in accordance with the foregoing general statement. Two subscribers' stations, 1, 2 are shown in 90 a connection assumed to have been established through a two-wire interoffice trunk link with the circuits and apparatus involved therein. A plug and jack switch 3 unites the calling line with an operator's 100 connecting circuit, which is divided as is usual into inductive sections by windings 4, 5 and 6, 7 of a repeating coil. The trunk end of this connecting circuit is united with a two-wire interoffice trunk line 8, 9 by 105 means of the contacts 10 and 11, say of an automatic switch. The trunk is divided at its incoming end into inductive sections by the windings 12, 13 and 14, 15 of another repeating coil. A battery 16, at the out- 110

going end supplies current to the calling line and to the trunk line loop. A battery 17, at the incoming end supplies current to the called line. A condenser 18, at the outgoing end completes the trunk loop as a telephonic link in the system of circuits between the two stations. Contacts 19, 20, which may also be assumed to be of an automatic switch, unite the called line section of the trunk with the called line.

10 The system of circuits is shown in its condition just following the operation of setting up the automatic switches and preceding the closure at certain contacts in the connecting circuit of the trunk loop between the offices. Sequence switches 21 and 22 are provided for controlling the operation of the circuits associated with the two automatic switches, indicated in the diagram by 15 the contacts 10—11 and 19—20, respectively. 20 To avoid unnecessary complication in a full disclosure of the invention, much of the apparatus involved in the preceding steps in the operation of the system, that is to say, preceding the setting up of the 25 connections shown in the diagram, is omitted. It is therefore assumed that in response to a call from substation 1, the operator had established a connection at the plug and 30 spring jack switch 3, had inquired of the calling subscriber the number of the party wanted, and had manipulated automatic switch sending apparatus or in some other manner had caused the connection to be set 35 up to the called station 2. The switches used in establishing this connection may be either manual or automatic, and the system as a whole may be manual, full automatic or semi-automatic, without departing from the 40 invention broadly, and the number of switches used in making a single connection is immaterial. It is assumed that the sequence switch 21 had, by successive stages, reached a resting position 11, and sequence 45 switch 22 a resting position 13. The succeeding resting positions of the sequence switch 21, involved in the operation to be described, are as follows: 14—ringing; 16—talking and 18—switch-restoring. The succeeding resting positions of the sequence switch 22 are: 16—talking and 18—switch-restoring. The master switch contacts 105 and 106 are arranged so that the sequence switches 21 and 22, after having been moved 50 out of one resting position, may be kept moving until the next resting position is reached.

Sequence switch 21 is moved out of position 11 by the momentary closure of a contact 23, which closure may be effected in any desired manner, preferably automatically upon the establishment of the connection shown in the drawing. In its advance to the ringing position 14, the sequence switch 55 21 closes at contacts 24 and 25 the trunk

loop between the offices. The trunk loop as a telephonic link, may be traced as follows: 16, 7, 26, 27, 25, 11, 9, 28, 29, 13, 18, 12, 8, 10, 24, 6, ground, and as a controlling circuit as follows: 16, 7, 26, 27, 25, 11, 9, 28, 29, 30, 31, 32, 8, 10, 24, 6, ground. A supervisory relay 26 at the operator's end of the trunk, and a trunk relay 33 at the incoming end of the trunk are energized. The former closes a circuit ground, 34, 35, 36, battery. The magnets 35 and 36, with their armatures, constitute an interlocking switch, and when both magnets are energized in the circuit thus traced, the armature 37 of magnet 35 being a little quicker than the armature 38 of magnet 36, prevents the latter from moving forward. A point extension 39 of the armature 37 engages the inside edge of the pointed end 40 of the armature 38. The trunk relay 33 acts to close a circuit for the motor magnet of the sequence switch 22, as follows: ground, 41, 42, 22, battery, and this sequence switch moves out of position 13 into the talking position 16. In passing position 14, sequence switch 22 closes a circuit as follows: ground, 43, 44, 45, battery. A by-path for contact 45 is provided in this circuit at the contact 46 of the relay 43 when the latter is energized, so that as the sequence switch 22 reaches position 16, the circuit just traced becomes ground, 43, 44, 46, battery.

The ringing of the called subscriber's bell may be effected automatically at this time as follows: A relay 47, held up by contact 102 in positions 13 and 14 of the sequence switch 22 is released as the sequence switch leaves position 14, closing a ground connection at contact 48 for a local ringing control circuit. Relay 47 was energized in position 12 of sequence switch 22 over a circuit from grounded battery, winding of relay 47, upper contact of 102, to ground. The contact 48 remains closed during the subsequent operations to be described. When the sequence switch 22 moves into position 16, this local ringing control circuit is closed through the ringing relay 51 as follows: ground, 48, 49, 50, 51, 52, 44, 46, battery. Ringing generator current is now applied to the called line over a circuit as follows: generator, 53, 54, 55, 56, 57, 20, 2, 19, 58, 59, ground. Current flows from generator 53 through the winding of the trip relay 54, ringing the bell at the station 2. Relay 54, however, is marginal and does not operate on the ringing current. It does operate however when the subscriber responds, due to the increased current in the telephone line, and then opens at contact 49 a shunt about the locking relay 60. The latter in turn closes at contact 61 a shunt about the relay 51. Relay 51 therefore reacts, opening the circuit of the ringing generator just traced, and closes the battery circuit to the 130

called line. This battery circuit includes a supervisory control relay 62 and is as follows: battery 17, 15, 62, 63, 57, 20, 2, 19, 58, 64, 14, ground. The supervisory control relay 62 now closes a circuit for a relay 67 as follows: ground, 65, 66, 67, battery. Relay 67 in turn closes two circuits for the control of an impulse relay 69 as follows: ground, 68, 69, battery and ground, 70, 71, 72, battery. Relays 71 and 72 are energized, the former opening at contact 66 the circuit of the relay 67. The latter is adjusted to release a brief moment after it is energized, say in about one-tenth of a second, so that the impulse relay 69 is given only a momentary impulse of current.

This momentary impulse of current in relay 69 causes a momentary interruption at contact 28 in the trunk circuit. In order to 20 avoid the release of the trunk relay 33 while the trunk circuit is thus interrupted, a circuit battery, 73, 74, ground, is closed at the same time, this circuit including a second winding 74 of the trunk relay 33. The 25 energization of relay 71 closes a locking circuit—battery, 72, 71, 75, 65, ground, which maintains relays 71 and 72 energized while the supervisory control relay 62 is energized.

The momentary interruption of current in 30 the trunk circuit thus occurring when the subscriber at station 2 closes his line to answer the call, causes a momentary reaction of the supervisory relay 26 at the operator's end of the trunk. This momentarily opens 35 the circuit through magnets 35 and 36, but the magnet 36 is equipped with a copper collar by reason of which it continues to attract its armature 38 after the circuit of its winding is interrupted. But the armature 37 of 40 magnet 35 releases quickly, so that armature 38 has time in which to move forward while the extension 39 is lifted. The local circuit of the magnets 35 and 36 is however quickly reclosed by the reenergization of relay 26, so 45 that armature 37 of magnet 35 is again attracted. The projection 39 then engages the outside edge of the pointed end 40 of the armature 38.

The sequence switch 21 is at this moment 50 in ringing position 14, and the operation just stated results in the closure of a local circuit—ground, 38, 76, 77, 21, battery, which causes the sequence switch to move out of position 14 into talking position 16.

55 While sequence switch 21 was resting in position 14, there had been closed a circuit, battery, 78, 79, 80, ground, which caused the lighting of the ringing lamp 79. The movement of the sequence switch 21 to position 16 opens this ringing lamp circuit, notifying the operator of the called subscriber's response, and closes a divided circuit as follows: battery, 78 thence in one path by way of 81, 82, 76, 38 to ground and in another path by way of the supervisory lamp signal

83 and 84 to ground. In this divided circuit, the supervisory lamp signal 83 is brought under control of the contact 76 of the magnet 36 and thereby under the control of the supervisory relay 26. At this time it is 70 shunted by resistance 81 in the path through the contact 76.

Subsequent openings and closings of the called subscriber's circuit which may be repeated indefinitely at the subscriber's switch hook, result in the lighting and effacing of the supervisory signal 83 in the following manner. Consider first the opening of the subscriber's circuit. This results in the re-action of the supervisory control relay 62, 80 and the opening at contact 65 of the then existing circuit through relays 71, 72. Relay 71 releases quickly, say in one-tenth of a second and relay 72 slowly, the latter in about four-tenths of a second, after the current is removed from its winding. This results in an impulse of current of about four-tenths of a second in the winding of relay 69, the circuit being as follows: ground, 85, 86, 69, battery. The trunk loop is thus again 90 interrupted at contact 28.

This time the interruption is of longer duration, say four-tenths instead of one-tenth of a second. The supervisory relay 26 again reacts, opening the circuit through 95 magnets 35 and 36. During this four-tenths of a second the slow release magnet 36 has sufficient time to release its armature 38, so that when the circuit is again closed at the termination of the interruption, the armature 37 of the magnet 35 again locks the armature 38 of the magnet 36 from forward movement. The opening of contact 76 allows more current to flow through the supervisory lamp 83, which now indicates to the operator that the called subscriber has hung up his receiver. A subsequent closing of the called line circuit operates to close contact 76 and effaces the signal 83, the operation being the same as previously described.

In the event that the called subscriber has responded and replaced his receiver, and then the calling subscriber wishes to have the operator recall on the called line, the operator may restart the automatic ringing 115 apparatus by momentarily depressing a ringing key 87. The operation is as follows: on pushing down the key 87 there is closed a contact 88, and a contact 89, the latter in a circuit ground, 89, 90, battery, which includes a relay 90. The relay closes contacts 104 and 103 and opens contact 27, establishing the following circuits: ground, 103, 26, 7, 16; and battery, 88, 104, 25, 11, 9, 28, 29, 30, 31, 32, 8, 10, 24, 6, ground. When 125 pressure is removed from the key, contacts 88 and 89 are opened, and relay 90 which is adjusted to release slowly, say in about one-tenth of a second, holds contact 27 open for that period and thus keeps the trunk loop 120

through winding 31 of trunk relay 33 momentarily open. At no time during the operation of relay 90 is the supervisory relay 96 released, as the contact 103 is made before contact 27 is broken. This momentary interruption of the trunk loop causes the trunk relay 33 to react momentarily, opening at contact 44 the circuit through relay 43 and the ringing control circuit through the locking relay 60. The latter relay reacts, opening at contact 61 the shunt about relay 51, and closing at contact 50 the shunt about itself. Relay 43, however, being of the slow release type, maintains its contacts 46 closed and its contact 91 open. Contact 44 of the trunk relay 33 being quickly reclosed, reestablishes the circuit through relay 43 so that this relay does not react. This contact also reestablishes the local ringing control circuit and again energizes the ringing relay 51, which again connects the ringing generator 53 in the circuit of the called line. The subscriber's bell is then rung until he responds again or until the operator proceeds to disconnect in the manner presently to be stated.

Disconnecting of the lines may be effected under either condition of the circuit of the called line, that is to say, whether the receiver is on or off the hook at the called station. Under either condition the trunk loop is closed through the winding 31 of the trunk relay 33. In a semi-automatic system, such as shown herein, the disconnect operation may be started by the operator removing the plug from the spring jack of the calling line. This act breaks a circuit at contact 92 of the plug and spring jack switch 3, in which is included a cord relay 93 and a cut-off relay 94. The reaction of the cord relay 93 opens battery circuit for the calling supervisory signal 91, and closes at contact 96 a circuit, battery, 21, 95, 96, ground, which causes the sequence switch 21 to move out of the talking position 16 into the switch-restoring position 18, wherein there is closed a circuit, battery, 97, 98, ground, which includes a restoring magnet 97 for the automatic switch that had previously established the trunk connections at contacts 10 and 11. As the sequence switch 21 moves out of position 16 it opens at contacts 24 and 25 the trunk loop. Trunk relay 33 thereupon reacts, and as the opening in this circuit is prolonged instead of being momentary as in the case of reringing, relay 43 has time to react and to close a circuit, ground, 99, 91, 100, 22, battery. This circuit includes the motor magnet of the sequence switch 22 which thereupon moves from its talking position 16 to its restoring position 18 wherein is closed a circuit, ground, 101, 102 battery, which includes a restoring magnet 110 for the automatic switch that had previously established

the connection at contacts 19 and 20 to the called line.

What is claimed is:

1. In a telephone exchange system, a trunk line forming a combined telephonic link and a controlling circuit, means for producing momentary current changes of like character in said circuit, a signaling device to be controlled over said circuit, and means responsive upon successive current changes for alternately displaying and effacing said signal. 75

2. In a telephone exchange system, the combination with a trunk and a line circuit inductively united, of a supervisory signal, 30 a switch for opening and closing the line circuit, means responsive upon both closing and opening the line circuit for producing momentary current changes of like character in the trunk circuit, and means responsive upon successive current changes for alternately displaying and effacing said supervisory signal. 85

3. In a telephone exchange system, the combination with a trunk and a line circuit inductively united, of a supervisory signal, 90 a switch for opening and closing the line circuit, means for producing momentary current changes of like character in the trunk circuit responsive upon both closing 95 and opening of the line circuit by said switch, and means responsive to the different current changes for effacing and displaying respectively said supervisory signal.

4. In a telephone exchange system, the combination with a trunk and a line circuit inductively united, of a supervisory signal, 100 a switch for opening and closing the line circuit, means for producing momentary current changes in the trunk circuit responsive upon both closing and opening of the line circuit, said current changes being of like character but differing in duration, and means responsive to the different current changes for effacing and displaying respectively said supervisory signal. 105

5. In a telephone exchange system, the combination with a trunk and a line circuit inductively united, of a supervisory signal, 110 a switch for opening and closing the line circuit, means for producing momentary current changes of short and of longer duration in the trunk circuit upon the closing and opening respectively of the line circuit, and means responsive to such current 115 changes for controlling said supervisory signal.

6. In a telephone exchange system, the combination with a trunk and a line circuit inductively united, of a supervisory signal 120 at one end of said trunk, an automatic ringing apparatus and a switch controlling magnet at the other end of said trunk, a plurality of current interrupting switches in said trunk circuit, means controlled by 125

- a succession of momentary interruptions at one end of said trunk circuit for controlling said supervisory signal, means controlled by a momentary interruption at the other end of said trunk circuit for controlling said automatic ringing apparatus, and means controlled by a prolonged interruption in said trunk circuit for operating said switch controlling magnet.
- 10 7. In a telephone exchange system, a trunk line forming a combined telephonic link and a controlling circuit, means for producing momentary current changes in said circuit, a signaling device to be controlled over said circuit, and means variably responsive to current changes of varying duration for alternately displaying and effacing said signal.
- 15 8. In a telephone exchange system, the combination with a trunk and a line circuit inductively united, of a supervisory signal, a switch for opening and closing a line circuit, means responsive upon both closing and opening the line circuit for producing

momentary current changes of varying duration in the trunk circuit, and means variably responsive to such current changes for alternately displaying and effacing said supervisory signal.

9. In a telephone exchange system, the combination with a trunk and a line circuit inductively united of a supervisory signal, a switch for opening and closing the line circuit, means for producing momentary current changes in the trunk circuit responsive upon both closing and opening of the line circuit by said switch, said current changes being different in duration, and means variably responsive to such current changes for effacing and displaying respectively, said supervisory signal.

In witness whereof, I hereunto subscribe my name this 7th day of December, A. D. 1914.

JOHN G. ROBERTS.
